CLAIM

The ornamental design for a wireless communication device for a personal data assistant, as shown and described.

DESCRIPTION

FIG. 1 is a top perspective view of a wireless communication device for a personal data assistant according to the present invention;

FIG. 2 is a top perspective view of a wireless communication device for a personal data assistant according to the present invention;

FIG. 3 is a top view thereof;

FIG. 4 is a right side view thereof;

FIG. 5 is a bottom view thereof;

FIG. 6 is a left side view thereof;

FIG. 7 is a front view thereof;

FIG. 8 is a rear view thereof;

FIG. 9 is a rear perspective view thereof; and,

FIG. 10 is a bottom perspective view.

The broken line showings of a personal data assistant in FIG. 1, and of various features on the communication device throughout the views, are for illustrative purposes only and form no part of the claimed design.
